(57) **CLAIM**

The ornamental design for a valve for a face mask, respirator, or the like as shown and described.

DESCRIPTION

FIG. 1 is a perspective view of a first embodiment of a valve for a face mask, respirator, or the like showing our new design from the front, bottom, right;

FIG. 2 is another perspective view thereof showing our new design from the rear, top, left;

FIG. 3 is a front elevation view thereof;

FIG. 4 is a rear elevation view thereof;

FIG. 5 is a left side elevation view thereof;

FIG. 6 is a top plan view thereof; and

FIG. 7 is a bottom plan view thereof.

FIG. 8 is a perspective view of a second embodiment of a valve for a face mask, respirator, or the like showing our new design from the front, bottom, left right;

FIG. 9 is another perspective view thereof showing our new design from the rear, top, right;

FIG. 10 is a front elevation view thereof;

FIG. 11 is a rear elevation view thereof;

FIG. 12 is a left side elevation view thereof;

FIG. 13 is a top plan view thereof; and,

FIG. 14 is a bottom plan view thereof.

(Continued)

The broken lines depict portions of the valve for a face mask, respirator, or the like that form no part of the claimed design.
